George I. Andersen, San Francisco, Calif., assignor to Andersen-Smith Milling Co., San Francisco, Calif., a corporation of California

Application April 21, 1939, Serial No. 84,458

Term of patent 14 years

To all whom it may concern:

Be it known that I, George I. Andersen, a citizen of the United States, residing in the city and county of San Francisco, State of California, have invented a new, original, and ornamental Design for an Edible Biscuit, of which the following is a specification, reference being had to the accompanying drawing, forming part thereof.

Referring to the drawing:

Fig. 1 is a perspective of the edible biscuit showing my new design;

Fig. 2 is a perspective of the edible biscuit as seen from the other side;

Fig. 3 is a front elevation of the edible biscuit; and

Fig. 4 is a side elevation of the edible biscuit.

I claim:

The ornamental design for an edible biscuit, as shown.

GEORGE I. ANDERSEN.
